UNITED STATES PATENT OFFICE.

MARTIN JONES, OF PHILADELPHIA, PENNSYLVANIA, ASSIGNOR OF ONE-HALF TO
JOSEPH S. MACLAUGHLIN, OF PHILADELPHIA, PENNSYLVANIA.

REPRODUCER.

1,415,361.

Specification of Letters Patent. Patented May 9, 1922.

Application filed June 19, 1917. Serial No. 175,628.

To all whom it may concern:

Be it known that I, MARTIN JONES, a citizen of the United States, residing in Philadelphia, Pennsylvania, have invented a Reproducer, of which the following is a specification.

One object of my invention is to provide a sound box or reproducer for talking machines which shall be capable of so affecting 10 the sound waves as to produce the required volume of sound without being as heavy as is at present the practice. By reason of the resulting lightening of the reproducer structure there is a reduction of the pressure upon 15 the record and a consequent increase in the useful life of the latter.

A further object of the invention is to so construct a sound box that it shall be capable of giving a more perfect and clearer reproduction of a given record than is now possible by the use of sound boxes of a similar type.

The invention also contemplates a novel arrangement and form of intermediate diaphragm whereby the above noted desirable results are obtained and also a construction whereby vibration of the body of the box is prevented or damped, as are also certain objectionable metallic noises commonly 30 produced when records of a certain class are played.

These objects and other advantageous ends I secure as hereinafter set forth, reference being had to the accompanying drawings, in which,

Fig. 1 is a plan of a sound box or reproducer constructed according to my invention;

Fig. 2 is a vertical section on the line 2—2, 40 Fig. 1; and

Fig. 3 is a plan of the auxiliary diaphragm forming part of my invention.

In the above drawings, 1 represents the body of a sound box which consists of a flat 45 disk or plate having a tubular boss 2 projecting from the center of one of its faces for attachment to the tone arm or horn of a talking machine. The opposite face of the body 1 has an outwardly projecting flange 3 whereby there is formed a shallow cylindrical cavity whose circular bottom has 50 cemented or otherwise closely held to it a thin, annular sheet 4 of dampening material such as hard or soft rubber, asbestos, gutta percha, or the like.

Parallel with but spaced away from this lining by a rubber gasket or washer 5 within the cavity of the body, is an auxiliary diaphragm 6, preferably consisting of a circular body of vulcanized fibre or equivalent material, of less diameter than the cavity of the body but having at opposite points projections 7 which rest upon the washer or gasket 5. A second gasket or washer 8 rests upon these projecting portions 7 and upon the intermediate portions of the washer 5 and this has the customary mica diaphragm 9 held to it by a metal ring 10 threaded into the cavity of the diaphragm;—there being a third washer or gasket 11 interposed between this 70 ring and the mica disk.

A stylus lever 12 of any desired construction has one end cemented to the center of the mica diaphragm and if necessary the auxiliary diaphragm 6 is centrally perforated to avoid contact with the adjacent projecting portion of its end. Said stylus lever extends radially outward from the center of the face of the sound box and has a transverse portion 13 engaged by a pair of trunnion screws 14 which pass loosely through a pair of lugs 15 respectively projecting up from the outer edge of the flange 3. Each trunnion screw however, has threaded upon it a pair of nuts 16 which cooperate with the 80 lug 15 to immovably hold said trunnion in any adjusted position. The outer portion 17 of the stylus lever is provided with an axial passage or recess for the reception of a needle and has a clamping screw 18 whereby 90 said needle may be rigidly held in place.

By repeated tests I have found that a sound box of the above described construction possesses advantageous features totally lacking in similar devices at present in use, 95 it appearing that the intermediate diaphragm 6 has such an effect upon the sound waves so that the most perfect reproduction of a record is obtained. As shown in the drawings, the diameter of the body of this 100 auxiliary diaphragm is such that there is an annular opening between the spaces in front and at the back of it, which opening is of course bridged by the supporting projections 7.

By the use of the rubber or other dampening lining the blare or metallic noise frequently heard in reproducing certain records are eliminated, this apparently being due to the fact that the vibration of the body of the 110

sound box is in a large measure prevented or damped. Moreover by the construction employed no metallic part of the sound box is exposed to the direct action of the sound waves produced.

By providing lugs 15 through which the trunnions pass loosely, but to which they are rigidly clamped by their respective pairs of jam nuts, I have found that the loosening 10 of the trunnions and their gradual disengagement from the stylus lever has been effectually prevented.

I claim:—

The combination in a sound box of a 15 body having a cylindrical cavity closed at

one end; a main diaphragm mounted across said cavity; a stylus lever attached to said diaphragm; an auxiliary diaphragm in the form of a relatively thin light disc of vulcanized fibre less in diameter than the cavity 20 of the sound box and having opposite edge projections; washers engaging said projections and supporting said latter disc in the space between the main diaphragm and the closed end of the cavity; and means for 25 holding said washers and diaphragms in position in the body.

In witness whereof I affix my signature.

MARTIN JONES.
